UNITED STATES PATENT OFFICE.

BRADFORD B. HOLMES, OF THE UNITED STATES ARMY.

PUMP.

Application filed September 3, 1919. Serial No. 321,352.

To all whom it may concern:

Be it known that I, BRADFORD B. HOLMES, a citizen of the United States, major, Coast Artillery, United States Army, stationed at 5 Washington, District of Columbia, have invented an Improvement in Pumps, of which the following is a specification.

My present invention relates more particularly to compression pumps such as are used in connection with refrigerating machines, and more particularly to pumps designed to form a part of small refrigerating machines of the compression-extension type adapted to household use.

Generally stated the pump element of such machines is designed to compress a gaseous fluid as, for instance, sulphur-dioxide and to expel it under compression into a condenser where it is liquefied.

For such purposes my present invention contemplates a motor-driven pump which I make leakless by employment of a flexible metallic bellows between the pump piston and cylinder. Preferably the dead space 20 between the metallic bellows and the cylinder wall is filled with oil or glycerine, both for the purpose of decreasing possibility of leakage of the gaseous fluid to be compressed, and also to decrease the clearance to any desired extent. If desired I may decrease the clearance space to nothing by employing a surplus of the oil.

The flexible metallic bellows may consist of a metal tube rolled or otherwise formed 35 with circular or helical convolutions or corrugations. The tube is thin enough and the corrugations deep enough and closely enough spaced to give the desired lengthwise flexibility required to permit full stroke of the pump piston without fatiguing the metal. The well known Fulton sylphon tubes may 40 be employed for this purpose where circular corrugations are desired, but I also contemplate utilizing tubes with helical corrugations which can be made by methods 45 other than those employed by Fulton.

I have discovered that when corrugated tubes, either the circular or helical type, are made of sufficient length with respect to the 50 piston stroke, all fatigue of the metal may be avoided and this element of the pump rendered practically immune to deterioration or wear; that no matter what length of tube is required for this purpose, the dead 55 space thus introduced in the compression

cavity can be eliminated by filling said space with oil as above described. Moreover, even though the tubes are of considerable length, and very flexible by reason of thinness of walls, depth, corrugation and length 60 of the tube, they will automatically tend to maintain a true cylinder outline with corresponding parts always equidistant from a straight line axis, when arranged so that the high compression takes effect on the exterior of the tube instead of on the interior, provided the two ends of the tube are kept 65 parallel with each other at right angles to and concentric with the axis. This of course requires that the piston element to which 70 the movable end of the tube is secured, be rigidly guided for movement in a line parallel with the axis of said tube.

In my device there are two fluids circulating through the pump circuit. One is the 75 gaseous medium to be compressed, and the other is the glycerine or oil. The oil is used in the pump to fill up the dead space, seal in the valves, to lubricate them, and to cut down clearance. This is an important feature 80 as it causes my pump to operate at maximum efficiency and with minimum electrical consumption.

The degree of compression of the gaseous fluid in my pump may be regulated within 85 wide limits by regulating the supply of oil to decrease or increase the clearance. As the clearance can be decreased to zero, the maximum compression attainable will be limited only by the power applied to the 90 driving mechanism by the motor, any desired lesser degree of compression being attainable by merely varying the back pressure on the outlet.

Other features of the device are automatic 95 lubrication of the pump driving mechanism and motor, silence and neat appearance. Furthermore, the apparatus is not complicated, requires no attention, is extremely durable, and not too expensive for general 100 use.

The above and other features of my invention may be more fully understood from the following description in connection with the accompanying drawings, in which:—

Figure 1 is a vertical central section in the plane of the axes of pump and drive shaft;

Figure 2 is a plan section of the top casting on the line 2—2, Figure 1;

100

110

Figure 3 is a plan view of the pump base casting showing the worm gear and crank pin for driving the pump in position therein.

As shown in these drawings, the motor, 5 pump and compression coil, which may be used as a condenser unit, together with motor for driving the pump, are shown as mounted on a single base plate 11. The electric driving motor 12 is shown as secured to said base 11. This motor drives the worm 13, and is connected to it by the flexible coupling 14, which may be any suitable type. The worm 13 rotates in the bearings 15 and 16 and against the thrust discs 17.

10 The worm engages with and turns the worm wheel 18, whose bearing 19 rotates in a bushing 20 held in its bed in the base casting 11 by the yoke 21.

15 The worm wheel 18 gives reciprocating motion to the pump piston 22 by means of the connecting rod 23. The worm wheel revolves in oil so that oil is carried to the rapidly rotating worm which throws oil spray about, lubricating the worm and worm

25 wheel bearings, the connecting rod bearings and the cylindrical guide 24 for the pump piston.

20 A small pipe 25 with two upright pipes 26 and 27 carry oil to two wicks (not shown) which lubricate the motor bearings.

30 An oil filler pipe and fittings 28 closed with a wing top plug 29 supplies an easy method of testing the lubricating oil level, and adding additional oil when necessary.

35 The entire external lubrication of the machine is thus supplied by pouring oil in the inlet 28.

Secured to the base casting 11, is an intermediate casting 30. This casting contains 40 the supports for worm bearings 15 and 16, cylindrical guide 24 for the pump piston, cooling water inlet 31, cooling water outlet 32, condenser pipe bushing 34, and, threaded sleeves 33, 33^a for the pump cylinder 35 and condenser cylinder 36.

45 The ends of the tube constituting the flexible metallic bellows 37, are cut off squarely at right angles to the main longitudinal axis of the tube and are secured by soldering or other means, one end to the piston element 22 and the other end to the casting 30, so that said bellows tube constitutes an internally extending hermetic closure for the sliding joint between the piston and cylinder elements of the pump. As before stated this bellows may be constructed from a metal tube rolled or otherwise formed with circular or helical convolutions deep enough and close enough spaced to give the desired 55 lengthwise flexibility.

50 The piston 22, pump guide 24 and bellows tube 37 are parallel so that the movable end of the tube 37 is parallel with the fixed end in all positions thereof. Hence reciprocation of the piston requires only uniform ex-

60 pansion and contraction of the corrugations of the tube in a direction parallel with the tube axis, and the tube is long enough so that the amount of bending of the metal is, at all points, well within the limits of fatigue 70 of the metal. The only other stresses taking effect on the bellows tube are external pressures applied with perfect uniformity through the oil or other medium filling the space between the bellows tube 37 and cylinder 35. Such pressures, though uniformly applied, are not uniformly resisted by the walls of the tube, since the latter can never be made perfectly uniform and symmetrical in construction, particularly as to thickness and resilience of the material. This might be expected to result in lateral bulging and crooking of the tube, and it does do 75 so when the pressure is internally applied. I have discovered, however, that when the 80 pressures are externally applied any inequalities of the resistances to the pressures are automatically compensated for so that the net result is not to crook the tube but, on the contrary, the external pressure will tend 85 to straighten out crooks in a previously crooked tube. Hence, it will be seen that an important feature of my invention consists in causing the high pumping pressures to take effect externally of the corrugated bellows tube, rather than internally thereof. 90 Approximately uniform atmospheric pressure is maintained within the bellows tube by openings 24^a communicating with atmosphere through the base of the engine. These 95 openings also permit access of lubricant to the interior of the bellows tube. As a result there is no tendency of the bellows tube to crook into engagement either with the piston guide which it surrounds, or with the 100 pump cylinder by which it is surrounded. Moreover, if the straightening effect of the 105 external pressure proves insufficient to prevent all contact, such contact as occurs will be slight and will be unproductive of wear 110 because of the above described arrangement for interior as well as exterior lubrication of the tube.

115 The top of pump cylinder 35 is threaded to take the top casting 38. The top end of condenser cylinder 36 is beveled, and as casting 38 is screwed down on cylinder 35, the beveled edge fits tightly against it making a water tight joint. The packing rings 39 and 40 assist in ensuring that the joint is 120 water tight.

125 The pump cylinder 35, intermediate casting 30, and top casting 38, are carefully threaded and the threads sealed with suitable thread filling compound and gaskets so that the joints between the cylinder and castings are gas tight.

130 Top casting 38 is supplied with the suction valve 41, suction valve housing 42, suction valve closing spring 41^a, suction valve

bushing 43, outlet valve 44, outlet valve wire retainer and spring 45, outlet valve seat 46, oil settling chamber 47, outlet passage 48, ball check valve inlet 49, inlet sealing plug 50, and cooling water outlet 32.

5 A suction pipe 56 is secured by bushing 43 to the top of the suction valve chamber, and a compression conduit which may be a condenser pipe 57, is soldered into a hole drilled 10 to meet the outlet passage 48. Suction pipe 56 leads from the source of fluid to be pumped or condensed, as for instance the evaporator of a refrigerating machine. Pipe 57 is coiled in the chamber between 35 and 15 36 and may constitute the condensing element of the refrigerator. Pipe 57 leaves said chamber through the bushing 34 and its outlet is controlled by valve 74.

Cooling water is admitted from the water 20 main to the condenser by pipe 58, and the warmed discharged condenser water drips away through pipe 59.

Reciprocation of the pump piston 22 causes the oil level in the pump chamber to 25 rise and fall, sucking in gas through pipe 56 and expelling it under pressure to the pipe 57 where it may be condensed by its pressure and by being cooled.

As gas is forced out of the pump chamber 30 through valve 44, it will tend to carry a little oil with it. Most of the oil settles out in the chamber 47, and a slight leak in the valve 44, purposely provided for by leaving the hole for the wire valve retainer 45 a little 35 large, allows a few drops of oil to drip back on the suction stroke into the pump chamber, thus ensuring always a slight excess of oil and, consequently, no clearance.

From the foregoing description it is evident 40 that this invention can be carried out in other forms by the use of other materials and other fluids than as above described. Therefore, I do not limit myself to the structure or materials described in the preferred 45 form, but include all other forms and materials by which this invention may be realized which are within the spirit of the invention and within the scope of my claims.

What I claim is:—

50 1. In a pressure pump apparatus, the combination of a pump chamber comprising a cylinder, a piston, and a metallic bellows secured at one end to said cylinder and at the other end to said piston; inlet and outlet valves, and a liquid filler completely filling 55 said pump chamber when the pump piston is at its nearest point to the cylinder head.

2. In a pressure pump apparatus, the 60 combination of two relatively movable pump elements; flexible metallic bellows connecting the same and forming therewith a gas pump chamber; suitable inlet and exhaust valves; and a liquid contained in said pump 65 chamber to reduce the effective clearance.

3. In a pressure pump apparatus, the combination of a pump comprising a cylinder element, a piston element and a metallic bellows secured at one end to said cylinder, and at the other end to said piston; a liquid 70 filler completely filling said pump chamber when the piston is at its nearest approach to the cylinder head; an inlet valve, and an outlet valve so constructed as to allow a slight leakage of liquid past said valve. 75

4. In a pressure pump apparatus, the combination of two relatively movable pump elements; flexible metallic bellows connecting the same and forming therewith a gas pump chamber; suitable inlet and exhaust 80 valves for said chamber; a liquid contained in said pump chamber to minimize the clearance; a reservoir beyond the discharge valve adapted to retain liquid passing the discharge valve; and a minute port leading 85 from said reservoir to said pump cylinder to lead liquid slowly from said reservoir back to said pump chamber.

5. In a pressure pump apparatus, in combination, a pump comprising two relatively movable pump elements and a metallic bellows secured to one of said pump elements at one end and to the other of said elements at the other end; the arrangement 90 of parts being such that the interior pump pressures take effect on the exterior of the bellows.

6. In a compressor, the combination of a gas pump having a discharge leading from its top; a liquid retaining separating-reservoir fed by said discharge; a bleed port leading from said reservoir back to said pump; and a top discharge from said reservoir. 100

7. A gas compressor comprising a chamber element and a piston element and means for relatively moving one with respect to the other, and a flexible metallic bellows secured to and extending between said elements parallel with the direction of their 110 relative movement and having the pressure of the compressed gas applied on the exterior of the bellows. 105

8. A gas compressor comprising a cylinder, a piston and means for guiding it within said cylinder, in combination with a corrugated, longitudinally flexible tube extending within said cylinder and secured at one end to said piston and at the other end over the open end of the cylinder, said tube being 115 coaxial with said cylinder and piston elements and arranged so that in operation the pressure of the compressed gas takes effect on the exterior of said tube. 120

9. A gas compressor comprising a pump 125 cylinder and, concentric therewith, a piston guide of substantially smaller diameter and less length extending inwardly from one end of said pump cylinder; a piston guided thereby, an approximately cylindrical, 130

- square-ended, thin-walled, deeply-corru-
gated, longitudinally-flexible, spring metal
tube located in the space between the cyl-
inder and piston guide secured at one end
5 to the piston and at the other end to an
anchorage surrounding the piston guide
opening in such relation as to be normally
without any substantial pressure of sliding
contact with adjacent exterior or interior
10 parts of the mechanism and to have gas
pressures generated by the compression
strokes of the pump taking effect on the ex-
terior of said tube.
11. A gas compressor comprising a pump
15 cylinder and, concentric therewith, a piston
guide of substantially smaller diameter and
less length extending inwardly from one
end of said pump cylinder; a piston guided
thereby, an approximately cylindrical,
20 square-ended, thin-walled, deeply-corru-
gated, longitudinally-flexible, spring metal
tube located in the space between the cyl-
inder and piston guide secured at one end
to the piston and at the other end to anchor-
25 age surrounding the piston guide opening
in such relation as to be normally without
any substantial pressure of sliding contact
with adjacent exterior or interior parts of
the mechanism and to have gas pressures
30 generated by the compression strokes of the
pump taking effect on the exterior of said
tube, and means for maintaining the in-
terior of said tube at a much lower pressure.
12. A gas compressor comprising a pump
35 cylinder and, concentric therewith, a piston
guide of substantially smaller diameter and
less length extending inwardly from one end
of said pump cylinder; a piston guided
thereby, an approximately cylindrical,
40 square-ended, thin-walled, deeply-corru-
gated, longitudinally-flexible, spring metal
tube located in the space between the cyl-
inder and piston guide secured at one end to
the piston and at the other end to anchor-
45 age surrounding the piston guide opening in
such relation as to be normally without any
substantial pressure of sliding contact with
adjacent exterior or interior parts of the
mechanism and to have gas pressures gen-
50 erated by the compression strokes of the
pump taking effect on the exterior of said
tube, and means for maintaining the interior
of said tube at a much lower pressure and
for lubricating said interior.
- 55 13. A gas compressor comprising a pump
cylinder and a piston concentric therewith,
means for reciprocating said piston through
an opening in one end of said cylinder to
vary the volume of compression space with-
in said cylinder, a suitably valved inlet and
outlet for said compression space, an ap-
proximately straight, square-ended, thin-
walled, circumferentially-corrugated, longi-
tudinally-flexible, spring-metal tube lo-
60 cated in the space between the cylinder and
the piston reciprocating means, secured at
one end to the piston and at the other end
to an anchorage surrounding the opening
through which the piston reciprocating
65 means extends, and arranged to have the
gas pressures generated by the compression
strokes of the pump take effect on the ex-
terior of said tube, the normal length of
the tube and the distance between the points
70 at which its ends are secured being very
great as compared with the stroke of the
piston.
14. A gas compressor comprising a pump
75 cylinder and a piston concentric therewith,
means for reciprocating said piston through
an opening in one end of said cylinder to
vary the volume of compression space with-
in said cylinder, a suitably valved inlet and
80 outlet for said compression space, an ap-
proximately straight, square-ended, thin-
walled, circumferentially-corrugated, longi-
tudinally-flexible, spring-metal tube located
in the space between the cylinder and the
85 piston reciprocating means, secured at one
end to the piston and at the other end to
an anchorage surrounding the opening
through which the piston reciprocating
means extends, and arranged to have the
90 gas pressures generated by the compression
strokes of the pump take effect on the ex-
terior of said tube, the normal length of the
tube and the distance between the points
at which its ends are secured being very
95 great as compared with the stroke of the
piston.
15. A gas compressor comprising a pump
100 cylinder and, concentric therewith, a piston
guide of substantially smaller diameter and
less length extending inwardly from one end
of said pump cylinder; a piston guided
thereby, the piston reciprocating means, se-
cured at one end to the piston and at the other
105 end to an anchorage surrounding the opening
through which the piston reciprocating
means extends, and arranged to have the
gas pressures generated by the compression
strokes of the pump take effect on the ex-
terior of said tube, the normal length of the
110 tube and the distance between the points
at which its ends are secured being very
great as compared with the stroke of the
piston, in combination with means for sup-
plying the power to reciprocate the piston,
including a power driven worm and a worm
gear provided with a crank pin adjacent
the said opening in the end of said cyl-
inder and the means for translating the crank
pin motion into reciprocating motion of the
piston consisting of a link extending from
said pin through said opening and connect-
ed to the piston at a point near the head
thereof.
16. A gas compressor comprising a pump
115 cylinder and a piston concentric therewith,
means for reciprocating said piston through
an opening in one end of said cylinder to
vary the volume of compression space with-
in said cylinder, a suitably valved inlet and
120 outlet for said compression space, an ap-
proximately straight, square-ended, thin-
walled, circumferentially-corrugated, longi-
tudinally-flexible, spring-metal tube lo-
cated in the space between the cylinder and
125 the piston reciprocating means, secured at
one end to the piston and at the other end
to an anchorage surrounding the opening
through which the piston reciprocating
means extends, and arranged to have the
gas pressures generated by the compression
strokes of the pump take effect on the ex-
terior of said tube, the normal length of
the tube and the distance between the points
130

at which its ends are secured being very great as compared with the stroke of the piston, in combination with means for supplying the power to reciprocate the piston, 5 including a power driven crank pin adjacent the said opening in the end of said cylinder and the means for translating the crank pin motion into reciprocating motion of the piston consisting of a link extending from said pin through said opening and connected to the piston at a point near the head thereof, and means for maintaining a body of oil in bathing relation to said crank pin for splash feed lubrication of the parts including the interior of said tube.

10 15. In a pressure pump apparatus, in combination, a pump comprising relatively movable pump elements and a metallic bellows secured to one of said pump elements 20 at one end and to the other of said elements at the other end; the arrangement of parts being such that fluid pressures created by the pump apply pressure on the exterior of the bellows.

25 16. A pressure pump apparatus including a reciprocating piston for applying pressure within the apparatus, means for operating it through an opening to the exterior, and means for sealing said piston against 30 escape of fluid, consisting of an imperforate, thin-walled, metal bellows tube, deeply corrugated circumferentially, secured air-tight at one end to the rear of said piston with its intermediate portion surrounding 35 the piston reciprocating element, and its other end secured air tight about said opening; and means affording fluid pressures which are much greater on the exterior of the tube than on the interior thereof, for 40 the purpose of keeping the tube straight.

45 17. A pressure pump apparatus including a reciprocating piston for applying pressure within the apparatus, means for operating it through an opening to the exterior, and 50 means for sealing said piston against escape of fluid, consisting of an imperforate, thin-walled, metal bellows tube, deeply corrugated circumferentially, secured air-tight at one end to the rear of said piston with 55 its intermediate portion surrounding the piston reciprocating element, and its other end secured air tight about said opening; and means applying fluid pressures of the pump on the exterior of the tube and approximately atmospheric pressures on the

interior thereof, for the purpose of keeping the tube straight.

18. In a pumping apparatus, a chamber adapted to contain fluids under pressure sealed against escape to the outer air, an 60 opening affording a passage from the exterior into the chamber cavity, a closure for said passage consisting of an imperforate, thin-walled, metal bellows deeply corrugated circumferentially, having one end 65 sealed air tight around said passage and the other end extending into the cavity within said pressure chamber, a reciprocating piston to the rear of which the inner end of said tube is secured air tight so that the 70 piston forms an air tight closure for said inner end, in combination with exterior driving means including a link extending through said passage and into said bellows and connected to impart predetermined 75 limited movement to said movable piston; and cooperating elements including the piston head on the inner side for utilizing within the chamber the relative movements imparted thereto from the outside thereof. 80

19. A chamber adapted to contain fluids under pressure sealed against escape to the outer air, an opening affording a passage from the exterior into the chamber cavity; a closure for said passage consisting of an 85 imperforate, thin-walled, metal bellows deeply corrugated circumferentially, having one end sealed air tight around said passage and the other end extending into the cavity within said pressure chamber, and a 90 relatively movable member to the rear side of which the inner end of said tube is secured air tight and for which it forms an air tight closure, in combination with exterior driving means extending through 95 said passage and into said bellows and imparting predetermined limited movement to said movable member; and cooperating elements on the inner side of said movable member for utilizing within the chamber 100 the relative movements imparted thereto from the outside thereof.

20. In the combination specified by claim 19, the further feature of a body of oil in contact with the outer surface of the bellows tube, operating to cushion and damp vibrations thereof.

In testimony whereof I have signed my name to this specification.

BRADFORD B. HOLMES.
